UNITED STATES PATENT OFFICE

ARTHUR E. MILLER AND CHARLES H. JOHNSON, OF SACRAMENTO, CALIFORNIA

KEY-EJECTOR MECHANISM

Application filed December 27, 1927. Serial No. 242,673.

Our invention relates to keys and has particular reference to a self ejecting key comprising mechanism whereby the key will be ejected from a lock after functioning to effect 5 the locking or unlocking of the same.

An object of our invention is to provide an ejector mechanism directly associated with the key, which will function to eject the key from the lock without necessitating a change 10 or modification of the standard lock casing or its associated parts.

A further object of our invention is to provide a self-ejecting key having mechanism associated therewith which will permit the 15 key to be readily inserted within a lock to effect the unlocking of the same and which will permit the key to remain inserted within the lock when the mechanism thereof is in unlocked position but which will forcibly 20 eject the key from the lock casing when the key is turned to return the mechanism thereof to locked position, thus preventing the possibility of unintentionally leaving the key within the lock when the mechanism is in the 25 locked position.

A still further object of our invention is to provide a self-ejecting key including mechanism adapted to eject the key from the lock, said mechanism being simple in construction, 30 reliable in operation, relatively easy and inexpensive to manufacture, and highly efficient in the purpose for which designed.

In the accompanying drawings, forming a part of this specification and in which is 35 shown several preferred embodiments of our invention,

Fig. 1 is a perspective view of a lock casing of a well known construction, showing our improvement in self-ejecting keys about to 40 be inserted therein, it being noted that in this disclosure the lock is assumed to be in locked position.

Fig. 2 is a horizontal sectional view of our self-ejecting key showing the spring, spring 45 cylinder and operating sleeve.

Fig. 3 is a vertical sectional view on the line 3—3 of Fig. 2.

Fig. 4 is a perspective view of a lock casing of well known construction, showing a modified form of our self-ejecting key about to be 50

inserted therein, it being noted that in this disclosure the lock is assumed to be in locked position.

Fig. 5 is a vertical sectional view of the modified form of our invention shown in 55 Fig. 4.

Fig. 6 is a vertical sectional view on the line 6—6 of Fig. 5.

Fig. 7 is a perspective view of a lock casing of well known construction, showing a further modification of our improvement in self-ejecting keys inserted and retained therein, 60 it being noted that in this disclosure the lock is assumed to be in unlocked position.

Fig. 8 is a disassembled view of the form 65 of our invention shown in Fig. 7 showing the spring, ejector cylinder and locking sleeve to be associated therewith.

Fig. 9 is a side elevation, partly in section, showing the assembled mechanism of the form 70 of our invention shown in Figs. 7 and 8, in its normal forward position.

Fig. 10 is a side elevation, partly in section, showing a further modification of our 75 invention as applied to another type of key.

Fig. 11 is a perspective view of the key and ejector mechanism shown in Fig. 10, showing the ejector cylinder in the position it assumes when the key is inserted within a lock to unlock the same, and 80

Fig. 12 is a vertical sectional view on the line 12—12 of Fig. 10.

Referring to the drawings, wherein like numerals are employed to designate like parts throughout the several views, the numeral 1 85 designates the face plate of a cylinder lock of standard construction suitably mounted on an escutcheon plate or other support 2. The face plate 1 is provided with the usual key-hole through which a key is adapted to be 90 inserted to lock or unlock the mechanism which the key is adapted to control. All of the above construction is old and well known in the art and forms no part of our present invention.

The form of our invention shown in Figs. 1, 2 and 3, comprises a key 3 ridged or grooved and otherwise formed to operate the tumbler or other mechanism of its associated lock, said key terminating at its rear end in a 100

flattened portion 4. A coiled compression spring 5 of an expanded length approximately equal to the length of the key from the flattened end portion 4 to the forward end of the key, surrounds the tumbler-operating portion of the key 3 and has its end convolution abutting the said flattened end portion 4. An ejector cylinder 6 is provided to surround the key 3 and to enclose the compression spring 5 mounted thereon, the forward closed end of this ejector cylinder 6 constituting an abutment for the forward end of the spring 5, and being provided with an opening 7 through which the tumbler-operating portion of the key 3 is freely slideable. The rear end of this ejector cylinder 6 is open and is provided with external screw threads 8. At diametrically opposite sides of the cylinder is a longitudinal slot 9, extending from the open end thereof to a point near the forward end of the cylinder, the flattened portion 4 of the key being slideable within these slots 9.

The flattened portion 4 of the key is welded or otherwise rigidly secured to the rear end 25 of an operating sleeve 10 having an internal diameter slightly greater than the outer diameter of the ejector cylinder 6 and having its outer surface knurled or roughened to provide a surface adapted to be engaged by the 30 operator's fingers. The ejector cylinder 6 has its rear or open end closed by a suitable cap 11, which screws on to the threads 8 at the rear end of the ejector cylinder 6, and which is preferably provided with an eyelet or the 35 like to permit the key to be attached to a key ring or key pack.

In assembling this form of our invention, the coiled compression spring 5 is placed within the ejector cylinder 6, the key 3 and its attached operating sleeve 10 is inserted within 40 the open end of the ejector cylinder 6 with the tumbler-operating end of the key 3 projecting slightly beyond the forward end of the cylinder and the flattened portion 4 of the key 45 sliding in the diametrically opposite slots 9. The cap 11 is then screwed on the threads 8, and this completes the assembling operation, it being noted that the association of parts is such that the spring 5 normally functions to 50 maintain the key within the cylinder and that the key may be projected from the cylinder by grasping the knurled operating sleeve 10 and moving the same longitudinally along the ejector cylinder 6.

55 In the form of our invention shown in Figs. 4, 5 and 6, the construction and method of assembly is substantially the same as that previously described except for the omission of the operating sleeve 10. In this modification, 60 the key 3 is provided with an enlarged flattened handle 4 at its rear end which extends into and through the longitudinal slots 9, where it may be grasped by the operator's fingers to project the key from the ejector cylinder 6. The flattened portion 4 of the key may

be undercut as shown at 12 in Fig. 5, so that the said flattened portion may be moved along the cylinder 6 beyond the forward ends of the slots 9 in the ejector cylinder 6.

In the forms of our invention shown in 70 Figs. 7 to 12 inclusive, the operating or hand-engaging portion of the key extends axially from the rear end of the ejector cylinder instead of radially through the sides thereof as shown in Figs. 1 to 6 inclusive. Referring to 75 Figs. 7, 8, and 9, the key has a shank 13, terminating at its rear end in a flattened handle 14 and having its forward end ridged or grooved and otherwise formed to operate the tumblers or other mechanism of the associated lock. At or near the center of the key shank there is formed integrally, or otherwise rigidly secured thereto, an annular collar 16 which extends transversely of the key and slightly beyond the surface thereof. A coiled 80 compression spring 17 of an expanded length approximately equal to the distance from the collar 16 to the forward end of the key, surrounds the tubular-operating portion 5 of the key and has its end convolution abutting the 90 annular shoulder 16. An ejector cylinder 18 is provided to surround the tumbler-operating portion 15 of the key and to enclose the compression spring 17 mounted thereon, the rear end of this cylinder being open and being provided with external screw threads 19. The forward closed end of this ejector cylinder is provided with an opening 20 corresponding in shape and size to the grooves, ridges or other formations of the tumbler-operating portion 15 of the key, whereby said portion is 95 freely slideable through the said opening, it being noted that the internal diameter of said cylinder is slightly greater than the diameter of the annular collar 16. Mounted on the rear 100 portion of the key shank 13 is a sleeve 21 internally threaded to engage the external threads 19 of the ejector cylinder 18, and having an end opening of a size slightly less than the diameter of the annular collar 16 and slightly greater than the rear portion of the key shank 13, whereby said sleeve is freely 110 slideable along said shank between the collar 16 and the handle portion 14.

The parts above described are assembled 115 as clearly shown in Fig. 9 of the accompanying drawings, the spring 17 surrounding the tumbler-operating portion 15 and being confined between the annular collar 16 and the forward closed end of the ejector cylinder 18, the sleeve 21 being screwed onto the threads 19 of the ejector cylinder 18, and the forward end of the key extending a slight distance through the opening 20 beyond the forward end of the ejector cylinder, it being 120 noted that the association of parts is such that the spring 17 normally functions to maintain the key within the cylinder and that the key may be projected from the cylinder by 125 moving the key longitudinally through the 130

cylinder against the pressure of the spring 17.

Referring to the form of our invention shown in Figs. 10, 11 and 12, it will be noted that the invention is shown as applied to an ordinary and common type of house key having a shank 13^a terminating at the rear end in a flattened handle 14^a and having its forward end 15^a ridged, grooved and otherwise formed to operate the tumblers or other

mechanism of its associated lock. At or near

the center of the key shank there is formed integrally or otherwise rigidly secured thereto, a disk 16^a which extends transversely of the key and is eccentrically disposed with relation to the axis of the key shank. A coiled compression spring 17^a of an expanded length

approximately equal to the distance from the disk 16^a to the forward end of the key, surrounds the forward portion of the key shank

and is confined between said disk and the forward closed end of an ejector cylinder 18^a whose internal diameter is slightly greater than the diameter of the disk 16^a. This ejector cylinder 18^a is provided at its rear open

end with external screw threads 19^a and has its forward closed end provided with an opening 20^a corresponding in shape and size to the grooves, ridges or other formations of the lock-operating portion 15^a, whereby said portion is freely slidable through said opening.

Mounted on the rear portion of the key shank 13^a is a sleeve 21^a internally threaded to engage the external threads 19^a of the ejector cylinder 18^a and having an eccentrically-positioned end opening of a size slightly greater than the diameter of the key shank 13^a, whereby said sleeve is freely slidable along said shank between the collar 16^a and the handle 14^a. The parts constituting this form of

our invention are assembled and function in a manner similar to that described in connection with the device shown in Figs. 7 to 9 inclusive and as clearly shown in Fig. 10.

Referring to the operation of the several

forms of our invention herein shown and described, and assuming that the key is to be used to open or unlock its associated lock mechanism, the key is inserted into the key-hole of the lock and the shank pushed inwardly until the lock engaging portions 3, 15 or 15^a are in proper position to actuate the lock mechanism. The key is then turned to the right or left and the lock mechanism is thereby actuated. The movement of the key

into the lock causes the forward end of the ejector cylinder 6, 18 or 18^a to abut against the face plate 1 of the lock and the continued inward movement of the key effected by the operating sleeve 10, or the handle portion 4, 14 or 14^a, forces said cylinder rearwardly along the key against the pressure of the compression spring 5, 17 or 17^a. When the key is moved inwardly the proper distance and turned to the right or left to actuate the mechanism of the lock, said key is retained

within the lock and cannot be withdrawn until it is returned to the initial position. As soon as this initial position is attained the key is free to be withdrawn from the lock and the compression spring 5, 17 or 17^a acting against the flattened portion 4, or abutment 16 or 16^a, functions to return the projecting lock-operating portion of the key into the cylinder 6, 8 or 18^a, and thus the key is forcibly ejected from the lock.

While any of the several forms of our invention is capable of general application to forcibly eject a key from its associated lock mechanism, it finds particular application in connection with key controlled switch mechanisms of the type usually used on automobiles to control the ignition system of the internal combustion engine propelling said vehicle. In such key controlled ignition system, it is customary to have the ignition switch controlled by a lock, into which a key may be inserted and turned to move the switch into the "on" position. In such construction the key is retained in the lock casting by the lock structure and cannot be withdrawn therefrom until moved to turn the switch to the "off" position. Motorists frequently turn the key to the "off" position and inadvertently leave the key in the lock when leaving the automobile and, hence many automobiles are stolen in this way. The novel form of key ejector mechanism covered in the present application makes it impossible to leave the key in the lock when turned to the "off" position, as the key is forcibly ejected from the lock casing just as soon as it has reached the "off" position.

It is to be understood that the form of our invention herein shown and described is to be taken as a preferred embodiment of the same and that various changes may be made in the shape, size and arrangement of parts without departing from the spirit of our invention or the scope of the subjoined claims.

Having thus described our invention, what we claim is:

1. An ejector mechanism for keys comprising a cylinder slidable along the key shank, an abutment on the key shank, and a spring interposed between the abutment and the forward end of the cylinder for normally retaining the cylinder over the tumbler-engaging portion of the key shank.

2. An ejector mechanism for keys comprising a cylinder slidable along the key shank, an abutment on the key shank, and a coiled compression spring surrounding the key shank within the cylinder and interposed between the abutment and the forward end of the cylinder for normally retaining the cylinder over the tumbler-engaging portion of the key shank.

3. An ejector mechanism for keys comprising a cylinder slidable along the key shank, a spring for normally retaining the cylinder

over the tumbler-engaging portion of the key shank, and means for moving the key shank axially against the action of the spring to project the tumbler-engaging portion of the key shank from the forward end of the cylinder.

4. An ejector mechanism for keys comprising a cylinder slidable along the key shank and normally surrounding the tumbler-engaging portion thereof, an abutment on the key shank, a compression spring interposed between the abutment and the forward end of the cylinder, and means for moving the abutment toward the forward end of the cylinder against the action of said spring when it is desired to project the tumbler-engaging portion of the key shank from the forward end of the cylinder.

5. An ejector mechanism for keys comprising a cylinder slidable along the key shank, the forward end of said cylinder being slotted to permit the tumbler-engaging portion of the key shank to be projected therethrough, an abutment on the key shank, a spring interposed between the abutment and the forward end of said cylinder for normally retaining the cylinder over the tumbler-engaging portion of the key shank with only a small section of the tumbler-engaging portion of the key shank normally projecting through the slot at the forward end of the cylinder, and means for moving the key shank axially against the action of the spring to project the remaining section of the tumbler-engaging portion of the key shank from the forward end of the said cylinder.

6. An ejector mechanism for keys comprising a cylinder slidable along the key shank and of a length corresponding substantially to the length of the tumbler-engaging portion of the key shank, said cylinder having a slotted forward end through which the tumbler-engaging portion of the key shank may extend and having its rear end screw-threaded, an abutment on the key shank at the rear of the tumbler-engaging portion thereof, a sleeve in rear of the abutment and screw-threaded to engage the threads on the rear end of the cylinder, and a coiled spring within the cylinder between the abutment and the forward end of the cylinder for normally retaining the cylinder over the tumbler-engaging portion of the key shank.

7. An ejector mechanism for keys comprising a cylinder surrounding the key and having its side wall provided with a longitudinal slot, a spring for normally retaining the cylinder over the tumbler-engaging portion of the key, and means extending through the slot and slidable therein for projecting the key from the cylinder against the pressure of the spring.

8. An ejector mechanism for keys comprising a cylinder surrounding the key and having its side walls provided with a longi-

tudinal slot, a spring for normally retaining the cylinder over the tumbler-engaging portion of the key, and an abutment on the key extending through the slot and slidable therein for projecting the key from the cylinder against the pressure of the spring.

9. An ejector mechanism for keys comprising a cylinder surrounding the key and having its side walls provided with a longitudinal slot, a spring for normally retaining the cylinder over the tumbler-engaging portion of the key, an abutment on the key extending through the slot and slidable therein, and an operating sleeve connected to said abutment and slidable along the cylinder for projecting the key from the cylinder against the pressure of the spring.

In testimony whereof we hereunto affix our signatures.
